UNITED STATES PATENT OFFICE.

HOWARD L. KENNEDY, OF FORT WAYNE, INDIANA.

TRAVELER'S GRIP OR BAG.

1,153,393.

Specification of Letters Patent. Patented Sept. 14, 1915.

Application filed July 22, 1914. Serial No. 852,347.

To all whom it may concern:

Be it known that I, HOWARD L. KENNEDY, a citizen of the United States, residing at Fort Wayne, in the county of Allen and State of Indiana, have invented new and useful Improvements in Travelers' Grips or Bags, of which the following is a full, clear, and exact description.

My invention relates to improvements in sheet metal travelers' grips or cases, and its object is to prevent moisture or rain entering the same when it is closed, and to this end to provide a hinge for the covers of a peculiar and economical structure which will not detract from the strength of the grip or case. This I accomplish by the means hereinafter fully described, and as particularly pointed out in the claims.

In the drawings: Figure 1 is a perspective view of a metal grip or kit to which my improvements are applied. Fig. 2 is a cross-section of a fragment of said grip, drawn to a larger scale, and embodying my invention. Fig. 3 is a view similar to that shown in Fig. 2, illustrating a modified construction of my improvements.

The general structure of the sheet metal grip or kit to which my improvements are applied is the same as that set forth in application for Letters Patent of the United States, filed June 8, 1914, Serial No. 843,675, and comprises a body-portion consisting of a suitable bottom, longitudinal side-walls A, and end-walls B. The upper edges of the latter extend above the top edges of the side-wall and are peaked, as shown, and the covers are hinged to the side-walls. One of said covers, D, extends to within a short distance of the truncated apex of the peaked upper edges of the end-walls B, and has its end edges flanged downward and adapted to lap over the inclined edges of one inclined edge of the peaked portion of said end-walls, when the grip is closed, substantially as shown. The other cover, E, extends from the side-wall, opposite that to which cover D is hinged, over the truncated apex of the peak, and down the opposite incline until it reaches the upper edge of cover D, whereupon it is flared outward slightly and overlaps the adjacent edges of the same. The end edges of cover D are also flanged downwardly and lap over the opposite inclined edges of the peak, as shown, and the meeting edges of these covers are locked

together by means of suitable locking devices, F, F, of a well-known type. At the ridge of cover E it is provided with a suitable handle G at about its center of length. These covers, D and E, have their lower portions a extend down past the upper edges of side-walls A, and the lower edges thereof are formed into knuckles b, b, that are pivotally connected by a wire pindle c to the knuckles d of the hinge-plates e. The latter extends up over and around the selvaged upper edge of the side-walls of the body of the grip and against the inner surface thereof, and are secured to said side-walls by rivets or otherwise. In Fig. 2, the upper portions of the side-walls extend upward beyond the meeting angle of the latter and the incline of the covers and the length of the hinge-plate is correspondingly increased so as to extend up over and around the upper edge of the inclined portion and to lap against the inner surface of the same. As thus constructed, it is impossible for rain or water to enter the grip through the hinged portion of the covers and grip.

In Fig. 3 of the drawings, the upper edge of the side-walls is shown to terminate at the angle of the inclined covers and side-wall, and in this event, the hinge-plate f does not have to be made as long as the hinge-plate e. This hinge-plate f, is secured to and laps against both the outer and inner surfaces of the upper portion of the side-walls in the same manner as it does in the construction shown in Fig. 2.

What I claim as new is: —

1. A sheet metal traveler's grip having a body comprising rectangular vertical longitudinal side-walls and end-walls which have their upper edges inclined upward from the sides to a central peak, and inclined covers hinged to the longitudinal sides below the upper edges of the latter, one of said covers having its upper edge extend over the peak of the top of the body and down the opposite incline and overlapping the top edge of the other cover and both of said covers having their lower marginal edges flanged downward to form vertical portions that overlap the top edges of the vertical side-walls of the body.

2. A sheet metal traveler's grip having a body comprising rectangular vertical longitudinal side-walls, end-walls which have their upper edges inclined upward from the

sides to a central peak, and inclined covers having their lower portions extend down past the upper edges of the said side-walls and lap against the outer surfaces thereof, and having their lower edges provided with 5 knuckles, hinge-plateslapping against the inner and outer surfaces and over the upper edges of the side-walls and having knuckles on the outer lower ends, and pintles connecting the knuckles of the covers to those of said hinge-plates; one of said covers having its upper edge extend over the peak of the top of the body and down the opposite incline and overlapping the top edge of the other cover and both of said 10 covers having their end edges flanged downward and overlapping the inclined top edges of the end-walls.

3. A sheet metal traveler's grip having a 20 body comprising rectangular vertical longitudinal side-walls, end-walls which have their upper edges inclined upward from the sides to a central peak, and inclined covers hinged to the longitudinal sides below the 25 upper edges thereof, one of said covers having its upper edge extend over the peak of the top of the body and down the opposite incline and overlapping the top edge of the other cover and both of said covers having 30 their lower marginal edges flanged downward to form vertical portions that overlap the top edges of the side walls of the body; the upper portion of said side-walls extending upward in an inclined direction toward

the peak of the top of the grip under the 35 covers.

4. A sheet metal traveler's grip having a body comprising rectangular vertical longitudinal side-walls, end-walls which have their upper edges inclined upward from the 40 sides to a central peak, and inclined covers having their lower portions extend down past the upper edges of the said side-walls that lap against the outer surfaces thereof, and having their lower edges provided with 45 knuckles, hinge-plateslapping against the inner and outer surfaces and over the upper edges of the side-walls and having knuckles on the outer lower ends, and pintles connecting the knuckles of the covers to those 50 of said hinge-plates; one of said covers having its upper edge extend over the peak of the top of the body and down the opposite incline and overlapping the top edge of the other cover and both of said covers having 55 their end edges flanged downward and overlapping the inclined top edges of the end-walls; the upper portion of said side-walls extending upward in an inclined direction toward the peak of the top of the grip under 60 the covers.

In witness whereof I have hereunto set my hand this 1st day of July, 1914.

HOWARD L. KENNEDY.
